ARTICLE FEEDING APPARATUS

Eugene M. Marchand, Bristol, Conn., assignor,
by mesne assignments, to General Motors Corporation, Detroit, Mich., a corporation of Delaware

Application June 11, 1932, Serial No. 616,678

13 Claims. (Cl. 51—215)

This invention relates to article feeding apparatus and comprises all of the features of novelty herein disclosed. An object of the invention is to provide improved apparatus for feeding or handling articles in connection with a machine for treating the articles, especially when the articles are to be passed through the machine a plurality of times. Another object is to provide improved apparatus for handling or feeding articles in a manner to avoid marring or nicking and with minimum exertion and attention by the operator. Another object is to provide a feeding apparatus which does not interfere with or obscure the operation of the connected machine and leaves the articles constantly accessible and visible to the operator for inspection. Still another object is to provide an improved hopper or bin. Another object is to provide improved conveyors or chutes for conducting articles from one point to another. Yet another object is to provide an improved apparatus for passing articles repeatedly through a centerless grinding machine. To these ends and also to improve generally upon apparatus of this character, the invention consists in the various matters hereinafter described and claimed. In its broader aspects, the invention is not necessarily limited to the specific apparatus selected for illustrative purposes in the accompanying drawings in which

Fig. 1 is a front elevation of the apparatus as applied to a centerless grinding machine.

Fig. 2 is a plan view of a portion of the apparatus.

Fig. 3 is a sectional view of a rotary hopper or bin.

Fig. 4 is a vertical sectional view of a modification, taken approximately on the line 4—4 of Fig. 5.

Fig. 5 is a horizontal sectional view taken approximately on the line 5—5 of Fig. 4.

Fig. 6 is a plan view of an auxiliary chute or conveyor.

Fig. 7 is a sectional view taken on the line 7—7 of Fig. 6.

Fig. 8 is a sectional view taken on the line 8—8 of Fig. 7.

The feeding apparatus is shown in connection with a centerless grinding machine in which the articles are rings or sleeves to be externally ground in a series of passes through the machine but this is merely illustrative of a preferred use. The numeral 10 indicates a frame on which a grinding wheel 12 and a regulating wheel 14 are rotatably mounted, the usual work-

supporting rails or guides 16 conducting the work-pieces W to the grinding throat. A bar 18 supports the usual loading slide 20 which is urged towards the grinding wheels by a cable 22 provided with a weight. Several of the work-pieces W are placed from time to time by the operator on the rails 16 between the rods 24 which carry pivoted dogs 26 so that a retraction of the slide 20 will allow the dogs to engage the last piece in a series so that, upon a subsequent advance of the slide, the work-pieces will be urged in a stream towards grinding position.

As the work-pieces pass between the wheels, they roll laterally one-by-one down an inclined chute 30 supported by forks 32 and 34 adjustably secured by set-screws in hollow standards 36. The chute 30 is curved and carries a pivot pin 40 for a chute 42 which can be elevated, as indicated in broken lines, to enable the operator to walk into a position next to the loading slide 20. The chute 42 is normally supported in gently inclined position by a fork 44 adjustably secured to a hollow standard 46. The chute is curved and its delivery end passes over and just clears the rim of a hopper or bin 50 which is mounted for rotation adjacent to the entrance end of the work guides 16.

The hopper or bin 50 has a hub or sleeve 52 closed at the top by a cap 54, suitable ball bearings 56 being interposed between the hub and a vertical post 58 which is clamped by a set screw in a hollow standard 60 on a base plate 62. The base plate also supports a tank 64 with a drain pipe fitting 66 for collecting grinding compound which may find its way with the work-pieces into the hopper or bin. The bin 50 has a bottom wall 70 and is divided into a number of compartments by radial partitions 72. In each compartment is a vertically movable pan or tray 74 having radial side walls, an arcuate outer wall 76, and a short wall section 78 connecting the radial walls. Each tray has a bottom wall 80 inclined downwardly towards the center of the hopper and provided with a drain opening 82 leading to the interior of a hollow plunger or guide sleeve 84 which is welded to the bottom wall and projects downwardly into the tank 64. Each tray also has a pair of downwardly projecting guide sleeves 86 which lie outside of the tank. All of the sleeves have tapered lower ends to facilitate passage through flanges or end caps 87 at the lower ends of guide casings 88 which are welded to the bottom wall 70 of the bin.

Coil springs 90 interposed between the end caps 87 and the bottom 80 of each tray elevate the tray when empty, as indicated at the left of Fig. 3, and hence articles coming from the delivery end 5 of the chute 42 drop through a small distance only. As the tray fills, it gradually lowers under the weight of the articles until it occupies the lowest position indicated at the right of Fig. 3. During the filling operation, the incoming articles drop first upon the elevated tray bottom 10 and then upon the preceding articles in the descending tray and so have only a small distance to fall. This avoids marring or nicking of the articles. While one tray is being filled, another 15 tray is being gradually emptied by the operator and the resulting decrease in weight of articles allows the coil springs 90 to elevate the tray. Hence the operator never has to reach very far 20 to get the articles for insertion in the loading slide 28. When a tray has been emptied, the operator turns the hopper or bin manually a portion of a revolution to bring a full tray to emptying position and the previously emptied tray to filling position.

25 To hold the bin 50 from undesired rotation, a brake shoe 92 on a plunger 94 is urged against the bottom of the bin by a coil spring 96. The plunger slides in a hollow casing 98 secured to a standard 99 and may be treadle-operated if desired to release the brake.

30 Figs. 4 and 5 illustrate a friction brake for application to the post 58. This brake comprises a series of friction washers 100 keyed to the post and alternating with larger washers 102 which 35 loosely surround the post and have their outer peripheries notched at 103 to interlock with the casings 88 on the bin. An abutment washer 104 is secured to the post 58 and another washer 106 is slidably mounted on the post and urged upwardly by a coil spring 108 to create the braking 40 pressure between the friction washers.

45 It is desirable to have the bin 50 low enough to cast no shadows or otherwise obscure the work in the grinding machine or other work-treating apparatus. The bin also should be high enough to make the work-pieces easily accessible for transfer to the work-treating apparatus. There also should be some difference in level between the top of the bin and the piece as it comes from the grinding wheels so that the piece will readily roll 50 by gravity. To get the advantages of a small difference in level without liability of the pieces failing to roll, I desirably provide, in some cases, an auxiliary work-lifting chute section which may be interposed at any desired point in the main chute or placed between the chute 42 and the bin. This device comprises outer side walls 124 and 55 inclined bottom sections 126 and 128 spaced apart at their rounded ends 130 and arranged at different levels. Each section is notched as at 132 to admit curved lifting fingers 134 on a rotary transferer or spider 136 whose hub is keyed to a drive shaft 137 projecting from a housing 138. The housing contains speed reducing gearing 60 driven from a variable speed motor 140 supported by a platform 142 on a post 144. A casing or guard 146 welded to the bottom sections 126 and 128 encloses the lower part of the spider and collects any dripping liquid which can be drained at the plug 148.

70 The side walls 124 desirably have false side walls or adjustable liners 150 to adapt the device for articles of different sizes. Screws 152, threaded in nuts welded to the walls 124, abut 75 against the liners to force them towards one

another to narrow the chute. Studs 154 are fixed to the liners and project through the walls 124 while coil springs 156 are interposed between the walls 124 and nuts on the studs to urge the liners outwardly against the screws 152. Each liner 5 has its uphill end bent laterally and lapped by a guide plate 158 which has a portion bent through a slot 160 in the side wall and attached to the outer surface of the latter. A chute 162 (which may be a part of chute 30 or of chute 42) has its 10 delivery end entered between the walls 124 in a position to register with the guide plates 158. As the work-pieces roll down the bottom section 126, the fingers 134 will elevate them one-by-one and deliver them at a higher level to the bottom section 128 from which they will roll with added impetus to another chute section or directly to the bin 50. Any grinding compound dropping from the work at the loading position is collected in a drip pan 164 and conducted to a tank 20 in the base of the machine.

I claim:

1. In a machine having a guide for presenting work-pieces thereto, a bin adjacent to the guide, means for conducting treated work-pieces from the machine to the bin, and means for elevating the work-pieces in the bin; substantially as described.

2. In a machine having a guide for presenting work-pieces thereto, a bin mounted for turning movement adjacent to the guide, a plurality of trays in the bin, means for elevating the trays, and means for conducting treated work-pieces from the machine to the trays; substantially as described.

3. In a machine having a guide for presenting work-pieces thereto, a bin mounted for rotation adjacent to the guide, a plurality of trays in the bin, springs acting to lift the trays, and means for conducting treated work-pieces from the machine to the trays in succession; substantially as described.

4. In a machine having a guide for presenting work-pieces thereto, a bin mounted for rotation and having its rim terminating adjacent to and lower than the guide, a chute receiving work-pieces from the machine and inclining downwardly towards the rim, a plurality of trays in the bin, and springs acting to elevate the trays; substantially as described.

5. In a machine having a guide for presenting work-pieces thereto, a bin near the entrance end of the guide, a chute for conducting treated work-pieces from the machine and inclining downwardly to the bin, and a work-lifting section in the chute; substantially as described.

6. In a machine having a guide for presenting work-pieces thereto, a bin near the entrance end of the guide, a chute for conducting treated work-pieces from the machine and inclining downwardly to the bin, and a rotary member in the chute and having work-lifting fingers; substantially as described.

7. In a centerless grinding machine having wheels forming a grinding throat and a work-guide extending to the throat, a container near the entrance end of the guide, a chute extending from the exit end of the grinding throat and inclining downwardly to the container, and means for elevating work pieces in the container to a point adjacent to the guide; substantially as described.

8. In a centerless grinding machine having wheels forming a grinding throat and a work-guide extending to the throat, a container near

the entrance end of the guide, a chute extending from the exit end of the grinding throat and inclining downwardly to the container, and the chute having a movable section to facilitate access to the guide; substantially as described.

5. In apparatus of the character described, a bin having a plurality of compartments, a tray in each compartment, a spring urging each tray upwardly in its compartment, a chute leading to the bin, and means for mounting the bin for rotation to provide for delivery of articles from the chute to the trays in succession; substantially as described.

10. In apparatus of the character described, a rotary bin having a plurality of compartments, a guide casing projecting from the bottom of each compartment, a tray in each compartment, a plunger attached to each tray and movable in the casing, and a spring urging the tray upwardly; substantially as described.

15. In apparatus of the character described, a rotary bin having a plurality of compartments, a tray guided vertically in each compartment and having an inclined bottom with a drain opening, and a tank below said openings; substantially as described.

20. In apparatus of the character described, a tray guided vertically in each compartment and having an inclined bottom with a drain opening, a hollow plunger attached to the tray around the drain opening, and a tank below said bin and receiving the plungers; substantially as described.

11. In apparatus of the character described, a

rotary bin having a plurality of compartments, a guide casing projecting from the bottom of each compartment, a cap on each casing, a plunger attached to each tray and movable in the casing, and a coil spring surrounding the plunger and interposed between the cap and the tray; substantially as described.

12. In apparatus of the character described, a rotary bin having a plurality of compartments, a tray guided vertically in each compartment and having an inclined bottom with a drain opening, and a tank below said openings; substantially as described.

13. In apparatus of the character described, a rotary bin having a plurality of compartments, a tray guided vertically in each compartment and having an inclined bottom with a drain opening, a hollow plunger attached to the tray around the drain opening, and a tank below said bin and receiving the plungers; substantially as described.

EUGENE M. MARCHAND.
